CHARLES W. SPONSEL, OF HARTFORD, CONNECTICUT, ASSIGNOR TO THE SPONSEL COMPANY, OF HARTFORD, CONNECTICUT, A CORPORATION OF CONNECTICUT.

STUD-RETAINING MEANS.

1,249,547.

Specification of Letters Patent. Patented Dec. 11, 1917.

Application filed April 19, 1917. Serial No. 163,187.

To all whom it may concern:

Be it known that I, CHARLES W. SPONSEL, a citizen of the United States, residing at Hartford, in the county of Hartford and 5 State of Connecticut, have invented certain new and useful Improvements in Stud-Retaining Means, of which the following is a specification.

This invention relates to what I shall for 10 convenience term stud-retaining means. Stud-retaining means involving the invention can be employed with advantage in many different connections, it being especially useful, however, in fields where the 15 part with which it is associated is subjected to jars, jolts and vibrations. As an illustration I might mention in this particular a universal-joint. In this use there are several studs, and the retaining means is preferably 20 associated with each. As may be inferred one of the primary motives I have in view is the provision of means certain and positive in action by which a stud can be effectively held in position and against rotary 25 and axial movements.

In the drawings accompanying and forming part of the present specification I have shown in detail a convenient form of embodiment of the invention which I will set 30 forth fully in the following description to enable those skilled in the art to practise the invention. I am not limited, however, to this particular disclosure; I may depart therefrom in several respects within the 35 scope of the invention defined by the claims following said description.

Referring to said drawings:

Figure 1 is a side elevation of a universal-joint equipped with stud-retaining means involving the invention, the casing of the joint being in section.

Fig. 2 is a detail view partly in elevation and partly in section of the cruciform coupling-member of the joint, several bearings 40 appearing, and associated with the same is stud-retaining means involving the invention.

Fig. 3 is a detail view of a screw.

Fig. 4 is a perspective view of a hollow 50 stud.

Fig. 5 is a like view of a disk.

Fig. 6 is a plan view of said disk.

Fig. 7 is a plan view, and

Fig. 8 a cross section of a portion of the

cruciform member to which I have already 55 alluded.

Like characters refer to like parts throughout the several views, which are on different scales.

In Fig. 1 I have shown the main members 2 and 3 and the cruciform coupling member 4 of a universal joint which presents in itself no part of the present invention, although as to one aspect thereof, it does constitute a feature, in that the stud-securi⁶⁰ 65 g means involving the invention act as a highly advantageous medium for pivotally uniting the cruciform coupling-member 4 with the main members 2 and 3 of the joint. These main members 2 and 3 may as shown 70 be forked, each fork comprising branches as 5. The branches 5 of the forks are as illustrated separate from but suitably connected with the respective main members 2 and 3. As will be clear, the fork of the member 2 75 is transverse or at right angles to the fork of the member 3 as common in universal-joints. The coupling-member 4 as will be understood is pivoted between the pairs of bearings 5 of the respective main members 2 80 and 3, by reason of which the latter are permitted to relatively move universally. I again wish to make clear that the stud-retaining or securing means while highly ad- 85 vantageous when incorporated in a uni- 90 versal-joint such as that briefly described, is capable of use in many other arts and especially in association with parts which are subjected to strains and stresses which ordinarily would tend to dislodge a pivot. 90

I will describe in detail merely one stud and its associated elements for pivotally connecting the cruciform coupling member 4 or its equivalent to a bearing as 5 or analogous part, it being clear that this description applies to the other three studs and their associated elements. In a universal joint, although it is not always necessary, I prefer to provide four of these studs such as 6. The coupling member has a cylindrical 100 opening as 7 which as shown is of two diameters, the portion of larger diameter being in register with a cylindrical or circular opening as 8 in the appropriate bearing 5 as best shown in Fig. 2. The cylindrical 105 hollow stud 6 it will be noted, extends entirely through the bearing opening 5 and partially into but does not bottom in the

portion of larger diameter of the cylindrical opening 7. In the construction shown the portion of larger diameter of the opening or bore 7 receives the disk 9 which as will be understood fits against the bottom of the larger portion of said bore 7. Said larger part of the bore has an undercut groove or channel 10 to receive a part of the periphery of the disk 9, the result being that when this relation is present, the disk will be locked against movement in the direction of the common axes of the openings or bores 7 and 8. As will be understood the bottom of the large part of the bore 7 presents the bottom of the undercut groove or channel 10. This disk 9 as shown is provided on its outer side with a projection 11 which as shown may be practically rectangular and which is eccentric to the disk 9, although this may not always be necessary. It is desirable, if not essential, however, that the opening 12 in the projection 11 should be eccentric to the disk, being in the organization shown back of the center or on the side thereof opposite to the marginal portion of the disk which enters the groove or channel 10. The vital consideration, therefore, is preferably that the hole or opening 12, the wall of which as shown is threaded, should be eccentric of the disk. The purpose of the tapped hole or opening 12 will be hereinafter explained, and I might observe that the hole preferably extends to the bottom of the disk. The projection 11 in addition to receiving the threaded portion of a pin or equivalent member as will hereinafter particularly appear is interlocked with the hollow stud, and this is obtained by interlocking the disk and stud for instance by fitting the projection 11 in a channel 13 in the under side of the stud or hollow pin 6, the projection 11 constituting a suitable key and the stud having a seat to receive the key which as may be inferred is a simple way of securing the desired condition. Extending through the hollow stud or pivot 6 is a screw 14, the inner end of which is tapered or of frusto-conical form to insure its easy application. This screw 14 has a head 16 to fit in the counterbore 17 in the outer end of the hollow stud 6, the body of the hollow stud having a bore or opening 18 to receive the body of the screw, said body between its ends being threaded as at 19 to match the threads of the opening 12. To prevent longitudinal displacement of the screw 14, it may be locked to the stud 6 in any desirable manner, for instance by the cotter pin 20 adapted for illustration to extend through registering perforations 21 in the outer end of the hollow stud 6 and to be also seated in the slot 22 in the head 16. Obviously the cotter pin 20 presents a convenient way of holding the screw 14 in assembled relation with the hollow stud 6.

65 I will describe how one hollow stud as 6

and its associated parts are mounted, this applying to the corresponding elements. Initially the disk 9 is dropped into the larger part of the bore 7 and its periphery interlocked with the channel or groove 10. When this is done the bore 7 is brought into coaxial relation with the bore or opening 8 when the hollow stud 6 is passed through the opening 8 and its inner or forward end interlocked with the disk by seating the projection 11 into the groove or channel 13. The screw 14 is now passed through the stud 6 until its threads 18 meet the threads of the hole or opening 12 when the screw 14 is turned to connect it with the disk 9. 80 When this is accomplished the cotter pin 20 is introduced, and when it is positioned, the parts will all be in correct relation and the hollow stud 6 will be effectually and positively held against turning and axial movements.

In a universal joint it is customary to provide for proper lubrication by incasing the main members 2 and 3, and for this purpose a casing such as 23 may be provided. This casing as may be inferred forms no part of the present invention, and I speak of it briefly merely because it is shown.

It might be noted that the disk 9 acts as a convenient nut, and I might also state that the cotter pin 20 provides a suitable way of uniting the stud 6 and screw 14 together.

I desire also to call attention to another important matter, that is the fact that the peripheral or marginal portion of the disk 9 by extending into the undercut 10 effectually prevents turning movement of the disk as well as movement thereof in the direction of the axis of the screw 14. The tapped hole 12 is eccentric to the disk 9 to an extent approximately equal to the maximum depth of the channel or groove 10, the consequence being when the disk bottoms in the channel or groove, the axis of the tapped hole will be coincident with the axes of the bores 7. 110 and 8.

What I claim is:

1. The combination of a hollow stud, a screw extending through and removably connected with said stud, and a nut with which the screw is connected, interlocked with the stud and having means associated with it to prevent turning movement and also movement in the direction of the axis of the screw.

2. The combination of a hollow stud, a screw extending through and removably connected with the stud, a nut with which the screw is connected, interlocked with the stud, and two elements connected pivotally by the stud and one of them being provided with means to prevent turning movement of the nut and also movement of the nut in the direction of the axis of the screw.

3. The combination of a hollow stud, a

5 screw extending through the stud and removably connected therewith, a nut with which the screw is connected, interlocked with the stud, and two bored elements, the bores of which register to receive the stud, one of the bores having a groove and the nut having a portion extending into the groove.

10 4. The combination of a hollow stud, a screw extending through the stud, a pin removably connecting the screw and the stud, and a nut with which the screw is connected, said nut being interlocked with the stud and having means connected with it to prevent the same from accidentally turning and also from moving in the direction of the axis of the screw.

15 5. The combination of a bored element, a nut fitted in the bore of the element and interlocked with said element, a screw in threaded connection with the nut, a hollow stud through which the screw passes, a second bored element through the bore of which the stud extends, the stud extending 20 into the other bore, and a pin for removably connecting the screw with the stud.

25 6. The combination of an element having a bore, a nut fitted in the bore element, said element being undercut, and the nut extending into the undercut portion, a second bored part, a hollow stud extending through the bore of the second bored part and into the first bore and interlocked with the nut, and a screw extending through the 30 stud and nut, in threaded engagement with the nut, the screw being pinned to the stud and extending into the first bore.

7. The combination of a hollow stud, a screw extending through the stud and removably connected therewith, a nut with 40 which the screw is connected, the nut having a projection and the stud having a groove to receive the projection, the nut also having means associated therewith to prevent its movement in the direction of 45 the axis of the screw and also to prevent its accidental turning.

8. The combination of a hollow stud, a screw extending through the stud, and a nut with which the screw is connected interlocked with the stud and having means associated with it to prevent turning movement and also movement in the direction of the axis of the screw.

9. The combination of a part having a 55 cylindrical bore, a nut supported by a wall of the bore, the nut having an eccentric tapped hole and the bore having an undercut groove to receive a peripheral portion of the nut, and the axis of the tapped hole 60 when said periphery is seated in said groove being concentric with the axis of the bore, a second bored part, a bushing extending through the bore of the second bored part and into the other bore and also interlocked 65 with the nut, and a screw extending through the bushing and in threaded engagement with the nut.

In testimony whereof I affix my signature in the presence of two witnesses.

CHARLES W. SPONSEL.
